THE NORRIS PETERS CO., PHOTO-LITHO. WASHINGTON, D. C.

UNITED STATES PATENT OFFICE.

WILLIAM T. SHAVER, OF DES MOINES, IOWA.

WAGON-BODY.

1,192,944.

Specification of Letters Patent. Patented Aug. 1, 1916.

Application filed May 11, 1914, Serial No. 837,788. Renewed January 3, 1916. Serial No. 70,080.

To all whom it may concern:

Be it known that I, WILLIAM T. SHAVER, residing at Des Moines, in the county of Polk and State of Iowa, have invented new 5 and useful Improvements in Wagon-Bodies, of which the following is a specification.

My invention relates to wagon bodies, and pertains more particularly to the means for locking the doors thereof when employed in 10 the transportation of valuables, such as mail wagons and the like.

The object of my invention is to produce a main locking means for said doors, and a supplemental lock operated from a different 15 part of the vehicle as an additional protection against unauthorized access.

Another object of my invention is to produce a double bolt for wagon doors adapted to be thrown by a handle from without, and 20 means for locking said handle at the rear of a wagon.

A further object thereof is to produce a lock for the rear door of a wagon having means for locking and unlocking same adjacent 25 the driver's seat, and a still further object of my invention is to produce a more simple, cheap and efficient device of said character than has heretofore been attained.

To these ends, my invention includes the 30 combination and arrangement of component parts to be hereinafter described and more particularly pointed out in the claims.

In the accompanying drawings, in which like reference characters indicate similar 35 parts, Figure 1 is a rear view of my wagon body, showing the locking means unlocked, Fig. 2 is a longitudinal sectional view of my wagon body, showing my door-locking means, and Fig. 3 is a plan view of the same.

40 Referring now to the drawings, 1 indicates the frame of the floor of my wagon body, comprising a rectangular frame of T-rails 2, suitably braced by the cross braces 3, and 4 and 4¹ designate the frame of the 45 side walls, which, as shown, comprises the rectangular frames of angle-irons 5¹ suitably braced and cross-braced by the vertically disposed T-rails 6¹ bolted at their ends to the angle-irons forming the frames 5¹, and 50 the horizontally disposed T-rails 7¹ which are likewise bolted to the angle-irons of the frames 5¹ at their ends, and interlocked intermediate thereof with the vertical T-rails 5¹.

55 The flanges 5^b on the vertical members of

the T-rails 5¹ and the flanges 7^b on the horizontal members, together with the flanges of the angle-irons 5¹ are provided with a plurality of perforations spaced a predetermined distance apart through which the 60 outer walls of the body may be removably bolted thereon. The front wall-frame 9 is likewise formed of a rectangular-frame of angle-irons suitably braced and cross-braced as in the side frames, and may be bolted 65 around its outer edges to the ends of the frames of the side walls.

As shown in the drawings, the top frame 10 is formed of a rectangular frame 11 of angle-iron, braced and cross-braced with 70 perforated T-irons 11^a, adapted to be bolted around its edges to the top member of the frames of the sides, and front and back walls.

As shown in the drawings, the side walls 75 12 and 12¹, and the front wall 13 of my body are formed of integral sheets of metal having a plurality of perforations 14 therein spaced to register with the perforations in the flanges of the angle-irons and T-rails 80 forming the frames therefor, by which they may be bolted in position or separately and independently removed therefrom for repairs or replacement; and the floor and roof thereof are likewise formed of sheets of 85 metal, likewise perforated and bolted to their frames, and it will be apparent that the roof may extend slightly beyond the edge of the walls to form an over-hang at 15, and that the base of the T-rail forming 90 the frame of the floor, will form a suitable sill 16 therefor.

The rear wall of my wagon body is formed of a rectangular frame 17 of T-rails, upon which are secured the plates 17¹ and 17^a, and 95 upon which are hinged the vertically disposed doors 18 and 19, the free edges of which abut and the free edge of door 18 projects over the edge of the opposite door 19 when closed and holds same from opening until released. For the purpose of locking said doors, I provide on the inside of door 18 the double acting vertically disposed bolts 25 and 26, each of which is pivoted at its inner end to one end of the arm 27, which, as shown, is rigidly secured intermediate its ends on the shaft 28. The inner end of said shaft is journaled on the bracket 29 mounted on the door, while the outer end projects through a suitable orifice in the door and 100 105 110

has secured thereon the looped head or handle 30 by which it may be turned and which is adapted to be locked, as hereinafter described.

It will be apparent that the turning of the arm 7 by the handle 30 will throw the bolts 25 and 26 outwardly or inwardly to engage or disengage the keepers 31 and 32 on the body of the wagon, and said bolts may pass through guides 33 on the inner face of the door intermediate their ends.

For the purpose of preventing the turning of the handle 30 to throw the bolts by unauthorized persons, I provide a hasp 33 swiveled on the door 18, having a slot intermediate its ends adapted to fit over the handle 30 when same is in position assumed when the bolts are locked, while a slot adjacent the end of the hasp fits over the staple 34 on the opposite door 19 to which it may be locked by a padlock of ordinary design.

For the purpose of latching the doors 18 and 19 by means controlled from a position adjacent the driver's seat, I provide the longitudinal shaft 35 carried on the depending brackets 36 and 37 adjacent the top of the wagon body. Said shaft projects through the front wall of the body and terminates in the crank 35'. On the opposite or rear end of the shaft is rigidly secured the oppositely turned double-ended hook 38 intermediate its ends. The ends of said hook are adapted to engage the eyelets 39 and 40 secured on the doors 18 and 19, respectively, and may be engaged or disengaged by turning the shaft 35 by the crank 35'.

The construction and operation of my locking device will be readily understood from the foregoing description and by reference to the accompanying drawings, and it will be appreciated that the parts thereof may be varied within the scope of the claims without departing from the spirit and scope of the invention.

Having thus described my invention, what I claim as new, and desire to be secured by Letters Patent, is—

1. The combination with a closed vehicle body having doors at the rear thereof, of a locking device for said doors, means for operating said locking device from the front of the vehicle adjacent to the driver's seat, a separate locking device for said doors, and means for operating said locking device from the rear of the vehicle, substantially as described.

2. The combination with a closed vehicle body having doors at the rear thereof, of a double-acting bolt for locking the doors having means for operating same from the rear, and a double-acting hook for locking said doors independently of said double-acting bolt having means for operating same from the front of the vehicle, substantially as described.

WILLIAM T. SHAVER.
